UNITED STATES PATENT OFFICE.

HIPPOLYT ROMANOFF, OF ST. PETERSBURG, RUSSIA.

DESIGN FOR A COMBINED CUPBOARD AND FOLDING WRITING-TABLE.

44,617.

Specification for Design.

Patented Sept. 2, 1913.

Application filed December 11, 1912. Serial No. 736,207. Term of patent 7 years.

To all whom it may concern:

Be it known that I, HIPPOLYT ROMANOFF, a subject of the Emperor of Russia, residing at St. Petersburg, in the Empire of Russia, (whose post-office address is 5 Wosnessenski Prospect, St. Petersburg, in the Empire of Russia,) have invented a new, original, and ornamental Design for a Combined Cupboard and Folding Writing-Table, of which the following is a specification, reference being had to the accompanying drawing, forming part thereof.

The figure is a perspective view of a combined cupboard and folding writing table in the open position, showing my new design.

No claim is herein made for the shape of the stand or support illustrated in broken lines.

I claim:

The ornamental design for a combined cupboard and folding writing table, as shown.

HIPPOLYT ROMANOFF.
